UNITED STATES PATENT OFFICE.

WILLIAM A. BOYD, OF DETROIT, MICHIGAN.

DESIGN FOR A JAR COVER OR SIMILAR ARTICLE

Application filed May 6, 1929. Serial No. 31,117. Term of patent 14 years.

To all whom it may concern:

Be it known that I, WILLIAM A. BOYD, a citizen of the United States, residing at Detroit, in the county of Wayne and State of Michigan, have invented a new, original, and ornamental Design for Jar Cover or Similar Article, of which the following is a specification, reference being had to the accompanying drawing, forming part thereof.

I claim:—

The ornamental design for a jar cover or similar article, as shown.

WILLIAM A. BOYD.
